(57) **CLAIM**

The ornamental design for a charging holder for robot vacuum cleaner as shown and described.

DESCRIPTION

FIG. 1 is a front perspective view of a charging holder for robot vacuum cleaner showing our new design;

FIG. 2 is a rear perspective view thereof;

FIG. 3 is a front elevation view thereof;

FIG. 4 is a rear elevation view thereof;

FIG. 5 is a left-side elevation view thereof, a right-side elevation view being a mirror image thereof;

FIG. 6 is a top plan view thereof;

FIG. 7 is a bottom plan view thereof; and,

FIG. 8 is a front perspective view of the charging holder for robot vacuum cleaner, shown in an environment of use.

The broken lines shown in FIGS. 1 to 7 depict portions of the charging holder for robot vacuum cleaner that form no part of the claimed design. The other broken lines shown in FIG. 8 depict environment and form no part of the claimed design.
